UNITED STATES PATENT OFFICE.

LAURENCE A. HAWKINS, OF SCHENECTADY, NEW YORK, ASSIGNOR, BY MESNE ASSIGNMENTS, TO THE UNION SWITCH AND SIGNAL COMPANY, A CORPORATION OF PENNSYLVANIA.

BLOCK-SIGNAL SYSTEM.

1,094,441.

Specification of Letters Patent. Patented Apr. 28, 1914.

Continuation of application Serial No. 495,100, filed May 10, 1909. This application filed August 7, 1909.
Serial No. 511,663.

To all whom it may concern:

Be it known that I, LAURENCE A. HAWKINS, a citizen of the United States, residing at Schenectady, county of Schenectady, State of New York, have invented certain new and useful Improvements in Block-Signal Systems, of which the following is a specification.

This case is in part a continuation of my 0 prior application, Serial No. 495,100, filed May 10, 1909.

My invention relates to alternating current block signal systems employing signals arranged to indicate danger, caution and clear, 5 either by a three position arm or by home and distant signals, and more particularly to systems in which the operation of a signal from caution to clear is produced by means of a switch included in the track circuit of the block guarded by the signal and actuated by the movement from danger to caution of the signal of the block in advance. Such a system is shown in Patent No. 845,220, issued to F. B. Corey, February 26, 25 1907.

The object of my invention is to improve the efficiency of such a system, and to remove certain disadvantages inherent in all prior systems of this character.

30 In the system shown in the above-mentioned patent two track relays of different types are employed for each block; one relay has a single winding supplied from the track circuit and responds to current of any phase, 35 while the other has two coöperating windings, one supplied from the track circuit and the other supplied independently of the track circuit with current of a certain phase, so that the current in the track circuit must have a 40 certain phase relation to the current in the second winding of the relay in order that the relay may operate. A relay of the latter type is more efficient than a relay with a single winding for the reason that the 45 greater part of the power required can be supplied directly and efficiently from the transmission line, while in the relay of the single winding type all the power must be supplied through the track circuit with con- 50 siderable loss. Furthermore, it is advantageous from the maintenance standpoint to have all the track relays of the same construction. By my invention all the relays may be of the efficient two-winding type. I

accomplish this result by supplying those 55 windings of the two relays which are not connected to the track circuits with currents differing in character, preferably of different phase. When one relay only is to be energized, that is, when the signal in advance is at danger, a current is supplied to the track circuit of such a character as to actuate one track relay only. When the signal in advance has moved to caution, the supply connections for the track circuit are 60 65 so changed that the current is then of a character adapted to operate both relays and preferably of a phase half way between the phases which would give maximum torque in the two relays respectively. Since 70 the phase of the track current is not reversed but only shifted through a certain angle (preferably approximately 90°) it is possible to arrange the switch controlling the 75 phase of the track current so as to shift the phase gradually without interrupting the flow of current to the track circuit. By means of such an arrangement a constant torque is maintained on the relay already energized, so that there is no danger of this 80 85 relay opening its contacts and tripping the signal while the switch is being actuated.

A very important advantage, resulting from the fact that the phase of the track current is not reversed, and that the relays 85 are of the two winding type is the possibility of avoiding by reversing the connections of the transformers for adjacent track circuits, all danger of false clear signals, 90 due to leakage from one track circuit to another by the breaking down of insulated joints, or otherwise. Since the relays can be energized only by current in a certain direction in the track windings, the leakage current from one section to another will be 95 cause of the reversal, be in such a direction as to create a reverse torque in the relays. This is of particular importance in alternating current systems, since the track voltages employed are ordinarily higher than 100 105 are used in direct current systems, and the insulated joints are therefore more likely to break down.

My invention will best be understood by reference to the accompanying drawings, in 105 which—

Figure 1 shows diagrammatically one embodiment of a block signal system arranged

in accordance with my invention; Figs. 2 to 7 inclusive are explanatory diagrams; Fig. 8 shows a modification of the system; Fig. 9 shows a modification adapted for use with cut sections, and Figs. 10 to 14 are explanatory diagrams.

In Fig. 1, A^0 to A^2 represent the track rails divided into four blocks which I have indicated as separated from each other by insulated joints, as in ordinary steam road practice. It will be understood, however, that my invention is applicable to electric roads having any suitable arrangement of track circuits. B represents a two-phase generator which supplies the current for the signal circuits through the transmission lines b, b', b^2 . I have indicated a two-phase three-wire transmission, the wire b serving as a common return for both phases. C to C^5 represent transformers having their primaries connected to the different phases of the transmission circuit and their secondaries adapted to be connected through impedances E to E^2 to the track. The way in which these transformers are connected will be described later. The impedances E to E^2 are provided for the purpose of preventing the transformers from being short-circuited by a train. D to D^5 represent track relays which are indicated diagrammatically as of the well-known induction type, each comprising a short-circuited secondary member d actuating the relay contacts, a winding d' connected to the track rails, and a second co-operating winding d^2 supplied with alternating current independently of the track circuits. These second windings of the relays and also the mechanisms of the home and distant signals F, F', F^2, G, G', G^2 , may be supplied from the secondaries of the same transformers that supply the track circuits. There are a pair of relays for each track circuit, and the windings d^2 of each pair of relays are connected to the secondaries of different transformers, so that the currents in the windings of the two relays are displaced from each other approximately 90° in phase. f represents a switch actuated by the home signal, as indicated diagrammatically by dotted lines, and controlling the operating mechanism of the distant signal. f' represents a movable contact or sector actuated by the home signal and provided with stationary contact fingers f^2, f^3 and f^4 . It is these fingers that control the phase of the currents supplied to the track circuit for the block next in the rear.

The operation is as follows: With a train in block A^2 , as represented in Fig. 1, the track windings of both relays D^4 and D^5 are short circuited, so that the relay contacts are open and signals F^2 and G^2 both stand at stop position. In this position of the signal F^2 the movable contact f' connects

contact fingers f^2 and f^3 . Through these fingers the secondary of transformer C^4 is connected to the track rails through one of the impedances E^2 . The relative phase of the currents in the windings of the relays D^2 and D^3 are then as shown by the diagrams of Figs. 2 and 3 respectively. In the diagram of Fig. 2 $o v'$ represents the phase of the secondary voltage of both transformers C^2 and C^4 , the first of which is connected to the winding d^2 of relay D^2 and the second to the track rails. If the impedance E^2 is non-inductive, the track circuit with this impedance in series with it has a fairly high power factor, so that the current supplied to the track circuit A' from transformer C^4 may be represented by $o i$ lagging behind the secondary voltage of transformer C^4 by the angle $v' o i$. The winding d^2 of relay D^2 has a comparatively low power factor, so that the current in this relay winding may be represented $o i'$. The current in the relay winding d' is the current in the rail circuit, that is, $o i$. There is, consequently, a phase displacement between the two windings of the relay D^2 represented by the angle $i o i'$, and if the circuits are suitably arranged this angle may be made equal to about 45° . If, as stated, the impedance E^2 is non-inductive, approximately this angle will be obtained with the precise connections shown. If the impedance E^2 is made inductive, so as to economize power, and the track current lags by a large angle behind the voltage, the proper phase angle between the currents in relay windings d' and d^2 may be obtained by adjusting the phase of the voltage impressed on the winding d^2 of relay D^2 , as will be obvious to those skilled in the art. Since two phase voltages from the secondaries of transformers C^2 and C^3 are available at relays D^2 and D^3 the phases of the voltages impressed on the windings of these two relays may readily be made anything desired. In relay D^3 the conditions are as indicated in Fig. 3 where the voltage and current impressed upon the winding d^2 of the relay are as indicated by $o v^2$ and $o i^2$, respectively, the current in the winding d' being the same as in the corresponding winding of relay D^2 and represented by $o i$. Comparing Figs. 2 and 3 it will be seen that the current in the winding d' , that is, $o i$, in each relay, is displaced about 45° from the current in the other winding, but in relay D^2 it leads the other current by 45° , while in relay D^3 it lags behind the other current by 45° . If the relays are so connected that a torque tending to close the relay contacts is produced when the current in the track winding leads the current in the other winding, then relay D^2 will have such a torque while relay D^3 will have a reverse torque. Under these conditions relay D^2 will close its contacts, clearing home signal F' , as

shown, while relay D^3 will have a reverse torque holding its contacts in open position so that distant signal G' will stand at stop, as shown. When the block A^2 is cleared 5 relay D^4 will close its contacts in the same manner as relay D^2 has closed its contacts, and the signal F^2 will begin to clear. When the contact f' reaches an intermediate position it engages all three fingers f^2 , f^3 and f^4 10 connecting transformers C^4 and C^5 in parallel across the rails of track circuit A' . While this connection lasts, some current flows through the two transformer secondaries in series, but it is limited in amount, 15 since it must flow through both impedances E^2 in series. So far as the effect on the track circuit is concerned, the voltage and current are in phase half way between what they would be with the transformers C^4 and 20 C^5 separately connected to the track. In other words, the current in the track circuit is advanced 45° in phase. This is shown in Figs. 4 and 5, in which the track current $o\ i$ is shown advanced 45° with respect to 25 Figs. 2 and 3. Conditions in relay D^2 , shown in Fig. 4, have not been changed, except to increase somewhat the relay torque, since the phase displacement of the currents in the two windings is now 90° instead of 30 only 45° . In relay D^3 , as shown in Fig. 5, the track current $o\ i$ is in phase with the current $o\ i^2$ in the other relay winding. The relay, therefore, has no torque, but its contacts are held open by gravity. As the signal F^2 completes its movement to clear position, the contact f' leaves contact finger f^2 , 35 opening the connections from the transformer C^4 to the track and leaving transformer C^5 alone connected to the track rails. 40 The conditions are then as represented at contact f' of signal F' and at relays D and D' , and the relative phases of the currents in the relay windings are as indicated in Figs. 5 and 7. The track current $o\ i$ now leads 45 the current $o\ i^2$ in the winding d^2 of relay D by 135° , so that the torque in relay D is the same as under the conditions first described for relay D^2 and shown in Fig. 2, since the sine of 135° is the same as the 50 sine of 45° . In relay D' there is a phase displacement of 45° between the track current $o\ i$ and the current in winding d^2 , that is, $o\ i^2$, as shown in Fig. 7, but the track current leads the current in the other winding 55 of the relay instead of lagging behind it, as in relay D^3 of Fig. 3, so that the relay D' has a torque causing it to clear the distant signal G . It will be seen that when the phase of the current in the track circuit is 60 shifted to energize the relay controlling the distant signal, the torque in the relay controlling the home signal is not destroyed even momentarily, so that there is no occasion for making the switch f' quick acting. 65 It will be noticed that the connections for

the transformers of adjacent track circuits are relatively reversed in adjacent blocks. This has not been mentioned in the foregoing discussion since the connections from the track windings of the relays are also relatively reversed, so that as far as the preceding discussion is concerned the relative phases of the currents are not affected by this double reversal. Reversal becomes of importance, however, upon leakage of current from one track circuit to another, either by breaking down of insulated joints, or otherwise, for it will be seen that any current leaking to relays D^2 and D^3 from either transformer C^2 or C^3 will be of a phase 70 opposite to $o\ i$ in Fig. 2 or Fig. 6, depending upon the position of the signal F' and contact f' at the time. In either case this current will be such as to produce a reverse torque in relay D^2 , and, if signal F' is clear, 75 in relay D^3 also, so that the signal F' , if not at stop position, will be thrown to stop position and signal G' , if not at stop position, will be thrown to stop position and retained there by the opening of contact f . 80 Thus, regardless of the phase of the current which is being impressed upon the track circuit no false clear indications can be obtained by leakage from one track circuit 85 to the other. 90

While in Fig. 1 it is the track windings of the relays that are shown relatively reversed in adjacent blocks, it is obviously immaterial which of the two windings are so reversed. 95

Fig. 8 shows a modification of the system, in which the operation is precisely the same as before described, the only differences between Figs. 1 and 8 being in details of arrangement. In the first place, one-arm three-position signals are shown for the purpose of giving the three indications, instead of the two-arm two-position signals of Fig. 1. This difference is wholly immaterial as regards my invention. In the second place, 100 instead of a two-phase transmission system, a three-phase transmission system is used, supplied by a three-phase generator B' , as shown, and the two-phase relation of voltages obtained on the secondary side of the 105 transformers C to C^5 by what is known as the "three-phase, two-phase connection" or "T connection" of the primaries. This also is immaterial with respect to my invention. The third difference between Figs. 1 and 8 110 is the addition of small transformers, c to c^2 inserted between the secondaries of the main transformers and the track. The advantage of employing this additional small transformer is that the same main transformers C to C^5 may be employed for a plurality of tracks, without introducing any electrical connection between the different tracks, a separate small track transformer, 115 being employed for each track circuit. The 120 125 130

impedances E to E^2 are placed in series with the secondaries of the main transformers and, therefore, on the primary side of the small track transformers. The impedances thus placed prevent short-circuiting of the main transformers just as if placed on the secondary side of the small track transformers and at the same time serve the same purpose as in Fig. 1 of preventing short circuiting of the main transformers by the contact f' when engaging both fingers $f^2 f^4$.

Fig. 9 shows the system modified for use with subdivided blocks or cut sections. The track circuits or sections A and A' compose one block, A^2 and A^3 another, etc. The arrangement at the signals is the same as shown in Fig. 8, except for minor changes in the circuit connections which have no effect on the operation. For the sections A and A^2 there are no signal mechanisms for controlling the phase, so this is accomplished by means of the track relays of sections A' and A^3 , respectively. The windings of these relays are connected the same as the windings of the relays at the signals, and their contacts are arranged to produce the same circuit changes as the contacts on the signal mechanism. This is shown diagrammatically in the diagrams of Figs. 10 to 14 which show the conditions in the five pairs of relays of Fig. 9. Fig. 10 corresponds to relays D^8 and D^9 in which the voltage and current in winding d^2 of relay D^8 are indicated by $o v'$ and $o i'$, respectively, and the voltage and current in the winding d^2 of relay D^9 by $o v^2$, $o i^2$, respectively. The track windings of the track relays are short-circuited, so that there is no current flowing through them and neither relay has any torque. Consequently, the transformer C^8 is connected to the primary of track transformer c^4 of track circuit A^3 , so that the current in the track circuit is as represented by $o i$ in Fig. 11, giving a torque in relay D^6 causing it to close its contacts and giving a reverse torque in relay D^7 . It will be noted that as long as a train was in section A^3 both relays D^6 and D^7 were deenergized and the opening of the contacts of relay D^6 disconnected the primary of track transformer c^3 from the secondaries of the main transformers C^6 and C^7 , so that relays D^4 and D^5 were then deenergized and the signal F' stood at stop position. With the energizing of relay D^6 , however, transformer C^6 is connected to the primary of transformer c^3 , so that the current in track circuit A^2 is of the same phase as that in track circuit A^3 and the conditions of relays D^4 and D^5 are as indicated in Fig. 12; that is, the same as the conditions of relays D^6 and D^7 in Fig. 11. Signal F' has, therefore, moved to caution position, first connecting the secondary of transformer C^5 in parallel with the secondary of

transformer C^4 and then opening the circuit of the latter transformer so as to leave the primary of track transformer c^2 connected to the secondary of the main transformer C^3 only. The phase of the track current in section A' is, therefore, as shown by $o i$ in Fig. 13, so that both relays D^2 and D^3 are energized, as indicated in Fig. 13. The energization of relay D^3 has connected the primary of track transformer c^2 to the secondary of transformer C^3 instead of transformer C^2 , so that the phase of the current in the section A is the same as that in section A' and the conditions in relays D and D' , shown by Fig. 14, are the same as in relays D^2 and D^3 , shown by Fig. 13. The contacts of relay D^2 are made flexible, as diagrammatically indicated, so that the front contacts are closed before the back contacts are opened, thus shifting the phase of the track current in the adjacent track circuit gradually without interrupting the flow of the track current. In other words, the contacts of this relay produce the same circuit changes in the same sequence as the movable contact f' , on the signal shaft. The same arrangement may obviously be repeated to operate blocks with as many cut sections as desired.

It will be noted in Figs. 8 and 9 that the circuit changes produced by the movement of contact f' occur while the signal is moving from danger to caution, which movement corresponds to the clearing of the home signal in Fig. 1. While the signal in Figs. 8 and 9 moves from caution to clear no change in circuit connections is produced. In the drawings the signals have been indicated diagrammatically in the usual conventional manner, the signal mechanisms themselves being omitted in order to prevent complicating the drawings. It will be understood in Figs. 8 and 9 that the conductor leading to the lower side of the blade is the common conductor for both the caution and clear positions, the circuit controlling the caution position being completed through the contacts of relay D , D^2 , etc., and the circuit controlling the clear position extending through the contacts of relay D' , D^3 , etc., in series with contacts of relays D , D^2 etc. If the signal mechanisms are single phase, the loads on the different phases of the transmission system may be balanced as indicated in Fig. 8, by connecting alternate signal mechanisms of the same track to different phases, or, in the case of roads having a plurality of tracks, the signal mechanisms for one track may all be connected to the same phase, as indicated in Figs. 1 and 9.

I do not desire to limit myself to the particular connections and arrangements nor to the particular difference in character of current or to the method of obtaining it shown and described but aim in the append-

ed claims to cover all modifications which are within the scope of my invention.

What I claim as new and desire to secure by Letters Patent of the United States, is

- 5 1. In a block signal system, signals for the blocks adapted to indicate danger, caution, and clear, track circuits for the blocks, sources of alternating current for the track circuits, a pair of track relays for each block
 10 controlling the caution and clear indications according as one or both relays are energized, said relays having windings supplied with current from the track circuit and co-operating windings supplied with alternating
 15 current independently of the track circuit, the currents supplied to said latter windings differing in character in the two relays of each pair, and means controlled by the presence or absence of a train in one
 20 block for controlling the character of the current supplied to the block in the rear of said means so as to actuate one only, or both, of the pair of relays for said block in the rear.
- 25 2. In a block signal system, signals for the blocks adapted to indicate danger, caution, and clear, track circuits for the blocks, sources of alternating current for the track circuits, a pair of track relays for each block
 30 controlling the caution and clear indications according as one or both relays are energized, said relays having windings supplied with current from the track circuits and co-operating
 35 windings supplied with alternating current independently of the track circuits, the currents supplied to said latter windings differing in character in the two relays of each pair, and connections including a switch actuated by the movement of a signal from
 40 danger to caution for supplying in one position of said switch to the rails of the block in the rear current of a character adapted to actuate one track relay only of said
 45 block and in another position of said switch for supplying to the said rails current of a character adapted to actuate both relays of said blocks.
3. In a block signal system, signals for the blocks adapted to indicate danger, caution, and clear, track circuits for the blocks, sources of alternating current for the track circuits, a pair of track relays for each block controlling the caution and clear indications according as one or both relays are
 50 energized, said relays having windings supplied with current from the track circuit and co-operating windings supplied with alternating current independently of the track circuit, the currents supplied to said
 55 latter windings differing in character in the two relays of each pair, the pairs of relays of adjacent blocks being reversely connected, and means controlled by the presence or absence of a train in one block for control-
 60 ling the character of the current supplied to the block in the rear of said means so as to actuate one only, or both, of the pair of relays for said block in the rear.
4. In a block signal system, signals for the blocks adapted to indicate danger, caution, and clear, track circuits for the blocks, sources of alternating current for the track circuits, a pair of track relays for each block
 65 controlling the caution and clear indications according as one or both relays are energized, said relays having windings supplied with current from the track circuit and co-operating windings supplied with alternating
 70 current independently of the track circuit, the currents supplied to said latter windings differing in character in the two relays of each pair, and connections including a switch actuated by the movement of a signal from danger to caution for supplying in one position of said switch to the rails of the block in the rear current of a character adapted to actuate one track relay only of said block and in another position for supplying of said switch to the said rails current of a character adapted to
 75 actuate both relays of said blocks, the sources and relays of adjacent blocks being reversely connected so that current from the source for one block produces a reverse torque in the adjacent relays upon the breaking down of the insulated joints between them.
5. In a block signal system, signals for the blocks adapted to indicate danger, caution, and clear, track circuits for the blocks, sources of alternating current for the track circuits, a pair of track relays for each block
 80 controlling the caution and clear indications according as one or both relays are energized, said relays having a winding supplied with current from the track circuit and a co-operating winding supplied with alternating current independently of the track circuit, one of said relays being responsive to a current in the track rails of a character to which the other does not respond, and connections including a switch actuated by the movement of a signal from danger to caution for supplying in different
 85 positions of said switch currents of different character to the track rails of the block in the rear, the sources and relays of adjacent blocks being reversely connected so that current from the source for one block produces a reverse torque in the adjacent relays upon the breaking down of the insulated joints between them.
6. In a block signal system, blocks having a plurality of cut sections, a track circuit for each cut section, signals for the blocks adapted to indicate danger, caution, and clear, means for supplying alternating currents differing in character for the track circuits,

3
a pair of track relays for each track circuit or section, having windings supplied with current from the track circuit and coöperating windings supplied with alternating current independently of the track circuit, the currents supplied to said latter windings differing in character in the two relays of each pair, the two relays of the first track circuit or section of each block controlling the 5 caution and clear indications of the signal for such block according as one or both relays are energized and the two relays of the track circuit or section next in advance controlling the character of the current supplied 10 to the first track circuit or section.

7. In a block signal system, blocks having a plurality of cut sections, a track circuit for each cut section, signals for the blocks adapted to indicate danger, caution, and clear, means for supplying alternating currents differing in character for the track circuit, a pair of track relays for each track circuit or section, having windings supplied with current from the track circuit and coöperating windings supplied with alternating current independently of the track circuit, the currents supplied to said latter windings differing in character in the two relays of each pair, the two 20 relays of the first track circuit or section of a block controlling the caution and clear indications of the signal for such block according as one or both relays are energized, means controlled by the presence or absence of a train in one block for controlling the character of the current supplied to the adjacent track circuit or section of the block next in the rear of said means, and contacts controlled by the two 25 relays of said last named track circuit or section for controlling the character of the current supplied to the track circuit or section next preceding.

8. In a block signal system, signals for the blocks adapted to indicate danger, caution, and clear, track circuits for the blocks, sources of alternating current for the track circuits, a pair of track relays for each block controlling the caution and clear indications according as one or both relays are energized, each of said relays having a winding supplied with current from the track circuit and a second coöperating winding supplied with alternating current independently of the track circuit, the currents supplied to said second windings differing in phase in the two relays of each pair, and means controlled by the presence or absence of a train in one block for controlling the phase of the current supplied to the block in the rear of said means so as to actuate one only, or both, of the pair of relays for said block in the rear.

9. In a block signal system, signals for the blocks adapted to indicate danger, caution,

and clear, track circuits for the blocks, sources of alternating current for the track circuits, a pair of track relays for each block controlling the caution and clear indications according as one or both relays are energized, 70 each of said relays having a winding supplied with current from the track circuit and a second coöperating winding supplied with alternating current independently of the track circuit, the currents supplied to 75 said second windings differing in phase in the two relays of each pair, and means controlled by the movement of a signal from danger to caution for gradually shifting the phase of the current supplied to the rails 80 of the block in the rear without interrupting the current flow.

10. In a block signal system, signals for the blocks adapted to indicate danger, caution and clear, track circuits for the blocks, 85 sources of alternating current for the track circuits, a pair of track relays for each block controlling the caution and clear indications according as one or both relays are energized, each of said relays having a winding 90 supplied with current from the track circuit and a second coöperating winding supplied with alternating current independently of the track circuit, the currents supplied to said second windings differing in phase 95 in the two relays of each pair, and connections including a switch actuated by the movement of a signal from danger to caution for supplying in one position of said switch to the rails of the block in the rear current 100 of a phase adapted to actuate one track relay only of said block and in another position of said switch for supplying to the said rails current of a phase adapted to actuate both relays of said blocks.

11. In a block signal system, signals for the blocks adapted to indicate danger, caution and clear, track circuits for the blocks, sources of alternating current for the track circuits, a pair of track relays for each block 110 controlling the caution and clear indications according as one or both relays are energized, each of said relays having a winding supplied with current from the track circuit and a second coöperating winding supplied 115 with alternating current independently of the track circuit, the currents supplied to said second windings differing in phase in the two relays of each pair, and connections including a switch actuated by the movement of a signal from danger to caution for supplying in one position of said switch to the rails of the block in the rear current of a phase adapted to actuate one track relay only of said block and in another position of said switch for supplying to the said rails current of a phase adapted to actuate both relays of said block and in an intermediate position of said switch for supplying currents both simultaneously so as to supply 125

to said rails a resultant current of an intermediate phase.

12. In a block signal system, signals for the blocks adapted to indicate danger, caution and clear, track circuits for the blocks, sources of alternating current for the track circuits, a pair of track relays for each block controlling the caution and clear indications according as one or both relays are energized, each of said relays having a winding supplied with current from the track circuit and a second coöperating winding supplied with alternating current independently of the track circuit, the currents supplied to said second windings differing in phase in the two relays of each pair by approximately ninety degrees, and means controlled by a train in one block for shifting the phase of the current supplied to the track circuit of the block in the rear of said means by approximately ninety degrees.

13. In a block signal system, signals for the blocks adapted to indicate danger, caution, and clear, track circuits for the blocks, sources of alternating current for the track circuits, a pair of track relays for each block controlling the caution and clear indications according as one or both relays are energized, each of said relays having a winding supplied with current from the track circuit and a second coöperating winding supplied with alternating current independently of the track circuit, the currents supplied to said second windings differing in phase in the two relays of each pair, the pairs of relays of adjacent blocks being reversely connected, and means controlled by the presence or absence of a train in one block for controlling the phase of the current supplied to the block in the rear of said means so as to actuate one only, or both, of the pair of relays for said block in the rear.

14. In a block signal system, signals for the blocks adapted to indicate danger, caution and clear, track circuits for the blocks, sources of alternating current for the track circuits, a pair of track relays for each block controlling the caution and clear indications according as one or both relays are energized, each of said relays having a winding supplied with current from the track circuit and a second coöperating winding supplied with alternating current independently of the track circuit, the currents supplied to said second windings differing in phase in the two relays of each pair, and means including a switch actuated by the movement of a signal from danger to caution for supplying in one position of said switch to the rails of the block in the rear current of a phase adapted to actuate one track relay only of said block and in another position of said switch for supplying to the said rails current of a phase adapted to actuate both relays of said block, the sources and relays

of adjacent blocks being reversely connected so that current from the source for one block produces a reverse torque in the adjacent relays upon the breaking down of the insulated joints between them.

15. In a block signal system, signals for the blocks adapted to indicate danger, caution, and clear, track circuits for the blocks, sources of alternating current for the track circuits, a pair of track relays for each block controlling the caution and clear indications according as one or both relays are energized, one of said relays being responsive to a current in the track rails of a phase to which the other does not respond, and connections including a switch actuated by the movement of a signal from danger to caution arranged for supplying in different positions of said switch currents of different phase to the track rails of the block in the rear, the sources and relays of adjacent blocks being reversely connected so that current from the source for one block produces a reverse torque in the adjacent relays upon the breaking down of the insulated joints between them.

16. In a block signal system, signals for the blocks adapted to indicate danger, caution, and clear, a polyphase transmission system for supplying current for the signal circuits, line transformers having their primary windings connected to the several phases of the transmission system, a track transformer for each block having its secondary connected to the track rails, means controlled by the presence or absence of a train in a block for shifting the primary connections of the track transformer of the block in the rear of said means from one line transformer secondary to another to vary the phase of the current supplied to the track rails of the block in the rear, and a pair of track relays for each block controlling the caution and clear indications according as one or both relays are energized, one of said relays being responsive to current in the track rails to which the other does not respond.

17. In a block signal system, signals for the blocks adapted to indicate danger, caution, and clear, a polyphase transmission system for supplying current for the signal circuits, line transformers having their primary windings connected to the several phases of the transmission system, a track transformer for each block having its secondary connected to the track rails, means controlled by the presence or absence of a train in a block for shifting the primary connections of the track transformer of the block in the rear of said means from one line transformer secondary to another to vary the phase of the current supplied to the track rails of the block in the rear, said means being arranged to establish one set of connections before breaking the other so as

- not to interrupt the flow of current to the track rails, impedances included in said connections to prevent short-circuiting the line transformer secondaries in changing from 10
 15 one set of connections to the other, and a pair of track relays for each block controlling the caution and clear indications according as one or both relays are energized, one of said relays being responsive to current in the track rails of a phase to which the other does not respond.

18. In a block signal system, signals for the blocks adapted to indicate danger, caution, and clear, a polyphase transmission 15 system for supplying current for the signal circuits, line transformers having their primary windings connected to the several phases of the transmission system, a track transformer for each block having its secondary connected to the track rails, means controlled by the presence or absence of a train in a block for shifting the primary connections of the track transformer of the block in the rear of said means from one 20 line transformer secondary to another to vary the phase of the current supplied to the track rails of the block in the rear, and a pair of track relays for each block controlling the caution and clear indications according as one or both relays are energized, each of said relays having a winding supplied with current from the track rails and a second coöperating winding supplied with alternating current independently of the 30 track rails, the currents supplied to said second windings differing in phase in the two relays of each pair.

19. In a block signal system, blocks having a plurality of cut sections, a track circuit for each section, signals for the blocks adapted to indicate danger, caution, and clear, sources of alternating current for the track circuits, a pair of track relays for each track circuit or section, one relay of 40 each pair being responsive to current in the track circuit of a phase to which the other relay does not respond, means controlled by the presence or absence of a train in one block for shifting the phase of the current supplied to the adjacent track circuit or section of the block in the rear of said means by approximately ninety degrees, and means controlled by the pair of relays for said track circuit or section for shifting the phase 50 of the current supplied to the track circuit or section next in the rear by approximately ninety degrees.

20. In a block signal system, blocks having a plurality of cut sections, a track circuit for each section, signals for the blocks adapted to indicate danger, caution, and clear, sources of alternating current for the track circuits, a pair of track relays for each track circuit or section, one relay of each 60 pair being responsive to current in the track

circuit of a phase to which the other relay does not respond, means controlled by the presence or absence of a train in one block for shifting the phase of the current supplied to the adjacent track circuit or section of the block in the rear of said means without interrupting the flow of said current, and means controlled by the pair of relays for said track circuit or section for shifting the phase of the current supplied to the track circuit or section next in the rear without interrupting the flow of said current. 75

21. In a block signal system, blocks having a plurality of cut sections, a track circuit for each section, signals for the blocks adapted to indicate danger, caution, and clear, means for supplying alternating currents differing in phase for the track circuits, and a pair of track relays for each track circuit or section, one relay of each pair being responsive to current in the track circuit of a phase to which the other relay does not respond, the two relays of the first track circuit or section of a block controlling the caution and clear indications of the signal for such block according as one or both relays are energized, and the two relays of the track circuit or section next in advance controlling the phase of the current supplied to the first track circuit or section and arranged to shift said phase approximately ninety degrees. 90 95

22. In a block signal system, blocks having a plurality of cut sections, a track circuit for each section, signals for the blocks adapted to indicate danger, caution, and clear, means for supplying alternating currents differing in phase for the track circuits, and a pair of track relays for each track circuit or section, one relay of each pair being responsive to current in the track circuit of a phase to which the other relay does not respond, the two relays of the first track circuit or section of a block controlling the caution and clear indications of the signal for such block according as one or both relays are energized, and the two relays of the track circuit or section next in advance controlling the phase of the current supplied to the first track circuit or section and arranged to shift said phase without interrupting the current flow. 100 105 110 115

23. In a block signal system, blocks having a plurality of cut sections, a track circuit for each section, signals for the blocks adapted to indicate danger, caution, and clear, means for supplying alternating currents differing in phase for the track circuits, and a pair of track relays for each track circuit or section, one relay of each pair being responsive to current in the track circuit of a phase to which the other relay does not respond, the two relays of the first track circuit or section of a block control- 120 125 130

- ling the caution and clear indications of the signal for such block according as one or both relays are energized and the two relays of the track circuit or section next in 5 advance controlling the phase of the current supplied to the first track circuit or section, the contacts of the last-mentioned relays being so connected that when both relays are deenergized the first track circuit is disconnected from the source of current, when one relay is energized current of one phase is supplied to said track circuit, and when both relays are energized current of another phase is supplied to said track circuit.
- 10 24. In a block signal system, blocks having a plurality of cut sections, a track circuit for each section, signals for the blocks adapted to indicate danger, caution, and clear, means for supplying alternating currents differing in phase for the track circuits, and a pair of track relays for each track circuit or section, one relay of each pair being responsive to current in the track circuit of a phase to which the other relay 15 does not respond, the two relays of the first track circuit or section of a block controlling the caution and clear indications of the signal for such block according as one or both relays are energized and the two relays 20 of the track circuit or section next in advance controlling the phase of the current supplied to the first track circuit or section, the contacts of the last-mentioned relays being so connected that when both relays are deenergized the first track circuit is disconnected from the source of current, when one relay is energized current of one phase is supplied to said track circuit, and when both relays are energized current of another 25 phase is supplied to said track circuit, the change from one phase to the other being made without interrupting the current flow.
- 20 25. In a block signal system, blocks having a plurality of cut sections, a track circuit for each section, signals for the blocks adapted to indicate danger, caution, and clear, means for supplying alternating currents differing in phase for the track circuits, a pair of track relays for each track 30 circuit or section, each having a winding connected with the track circuit and a coöperating winding supplied with alternating current independently of the track circuit, the currents supplied to the last named windings differing in phase in 35 to said second windings differing in phase in 55 the two relays of each pair, the two relays of the first track circuit or section of a block controlling the caution and clear indications of the signal for such block according as one or both relays are energized and the two relays of the track circuit or section next in advance controlling the phase of the current supplied to the first track circuit or section.
- 35 26. In a block signal system, blocks having a plurality of cut sections, a track circuit for each section, signals for the blocks adapted to indicate danger, caution, and clear, means for supplying alternating currents differing in phase for the track circuits, a pair of track relays for each track circuit or section, each having a winding supplied with current from the track circuit and a second coöperating winding supplied with alternating current independently of the track circuit, the currents supplied to said second windings differing in phase in 60 the two relays of each pair, the two relays of the first track circuit or section of a block controlling the caution and clear indications of the signal for such block according as one or both relays are energized and the two relays of the track circuit or section next in advance controlling the phase of the current supplied to the first track circuit or section.
- 40 27. In a railway signaling system, a track circuit, a source of alternating current, a pair of relays each having a winding connected with the track circuit and a coöperating winding supplied with alternating current independently of the track circuit, the currents supplied to the last named windings differing in character, and means for supplying currents of different character from the source to the track circuit whereby 65 one or both of the relays will be operated.
- 45 In witness whereof, I have hereunto set my hand this 5th day of August, 1909.
- 50 LAURENCE A. HAWKINS.

EDWARD WILLIAMS.

Corrections in Letters Patent No. 1,094,441.

It is hereby certified that in Letters Patent No. 1,094,441, granted April 28, 1914 upon the application of Laurence A. Hawkins, of Schenectady, New York, for an improvement in "Block-Signal Systems," errors appear in the printed specification requiring correction as follows: Page 5, lines 89, strike out the words "for supplying", and same page and line, after the word "switch" insert the words *for supplying*; page 6, line 129, after the word "supplying" insert the word *both*; same page line 130, strike out the word "both;" and that the said Letters Patent should be read with these corrections therein that the same may conform to the record of the case in the Patent Office.

Signed and sealed this 23rd day of June, A. D., 1914.

[SEAL.]

R. F. WHITEHEAD,

Acting Commissioner of Patents.
